UNITED STATES PATENT OFFICE.

ANTOINE PADOUÉ FILIPPI, OF PARIS, FRANCE.

DRIVING AND SUSTAINING SURFACES APPLICABLE TO NAVIGATION IN AIR AND WATER.

1,103,188.

Specification of Letters Patent. Patented July 14, 1914.

Application filed June 24, 1912. Serial No. 705,560.

To all whom it may concern:

Be it known that I, ANTOINE PADOUÉ FILIPPI, a citizen of the French Republic, residing at 132 Avenue du Maine, Paris, France, civil engineer, have invented certain new and useful improvements in Driving and Sustaining Surfaces Applicable to Navigation in Air and Water, of which the following is a specification.

10 It is known that when a surface (or rotatable plane) of a certain form having suitably curved or bent edges is rotated in the air in a direction in which the forward or upper edge of the surface or plane moves foremost, the rotation gives rise to a reduction of pressure on the forward or upper face of the surface; the pressure on the opposite face remaining nearly constant, there results a tendency for the displacement of 20 the surface or plane in the direction of the greatest reduction of pressure. Surfaces or planes, specially intended to produce this phenomenon with great intensity are described for example, in the specifications of 25 the United States Patents Nos. 920,554, 1,082,327 and application for patent, Serial Number 616,712.

The present invention has for its object a method of assisting the reduction of pressure resulting from the phenomenon hereinbefore described; the method consists essentially in directing to the center of the forward or upper face of the surface a current of air or other fluid having a sufficient speed 35 to sweep over this surface and to increase the speed with which the air passes away from the center.

The accompanying drawings illustrate several arrangements by which the invention may be carried into effect.

Figure 1 is a vertical diagrammatic section showing an arrangement adapted to direct air or other fluid above a rotatable sustaining surface. Fig. 2 is a vertical diagrammatic section of a modification in which the air is directed above the surface from a pipe specially provided for the purpose. Fig. 3 is a vertical diagrammatic section to a larger scale, showing, by way of example, a device capable of being applied so as to direct the air from a fan into the hollow shaft (as shown in Fig. 1). Fig. 4 shows diagrammatically a device for directing air below 55 the surface as well as above it; Fig. 5 is a

diagrammatic elevation of an apparatus of the helicopter type with sustaining surfaces constructed according to the invention; finally Fig. 6 shows in plan a surface with curved or bent edges and provided with a deflecting plate for the air which insures the necessary reduction of pressure.

In the construction shown in Fig. 1, the shaft 1 of the sustaining surface 2 is hollow; it is prolonged at its lower part below the bevel pinion 3, as is shown more clearly in Fig. 3, so as to receive the pipe which directs the air drawn in by the fan 4. This fan may be mounted, as shown in Fig. 1, on the shaft of the motor 5, this shaft also carrying at its extremity the bevel pinion 6.

Above the surface 2 and at a certain distance from this surface is fixed a screen or deflecting plate 7 of suitable dimensions. The air, drawn in by the fan 4 and passing through the hollow shaft 1 as indicated by the arrow F, is broken up against the screen 7 and escapes in the direction of the arrows F', sweeping across the forward or upper face of the surface 2 (according as it acts 80 as a driving or as a sustaining surface) 2 and thus increasing on this face, the phenomenon of the reduction of pressure hereinbefore mentioned.

When, for any reason whatever, it is desired to avoid directing the fluid through the shaft provided for the surface, use may be made of the modification shown in Fig. 2. In this modification the fluid drawn through the fan passes through the tube 8 which is divided into two branches 9 and 9'; each of these branches is terminated as shown in Fig. 2 by a small elbow and by a plate or disk 10, 10', which acts in a similar way to the screen 7 in Fig. 1; it will be understood in fact that the fluid passing through the fan and arriving through the pipes 9 or 9' is forced to pass over the upper face of the surfaces 2, in the direction of the arrows F'. In Fig. 2 I have supposed that there are two motors 5; it is needless to say that the device could also be constructed with a single motor driving the fan 4 and effecting the rotation of the wings 2, 2.

Fig. 3 shows, by way of example, one of the devices which may be applied in order to direct into the hollow shaft 1, the fluid drawn in by the fan 4, while allowing of the rotation of the shaft 1. As will be seen in 110

this figure, the shaft 1 is prolonged at the lower portion below the pinion 3, and is surrounded by a fixed sleeve 11. A ball race 12 disposed between the sleeve and the shaft 1, allows of the free rotation of the shaft 1 in the sleeve. A fixed pipe 13, which may terminate, as shown in the figure, in a nozzle of truncated form for example, penetrates to the lower part of the shaft 1 and directs the air drawn in by the fan.

When the rotatable plane to which the invention is applied rotates and advances at a great speed, there is produced at the center of the rear portion, a partial vacuum resulting from the speed of rotation of the plane and from its displacement in the air; it is evidently advantageous to reduce or destroy this partial vacuum since the force which produces the advance results from the difference between the pressure existing on the forward face and the pressure existing on the rear face of the plane; now, since the pressure existing on the rear face cannot be greater than the atmospheric pressure, it is advantageous to maintain this pressure as near as possible to the atmospheric pressure; it is for this purpose that the device which is shown in Fig. 4 has been provided; part of the air drawn in by the fan is directed, as has been hereinbefore described, in the direction of the arrow A, to the front face of the plane against the screen 7; another volume of this air passes in the direction of the other arrows into a tube B concentric with the shaft 1; this air serves to raise the pressure under the plane in the part a—b.

Fig. 5 shows how the invention may be applied to an apparatus of the helicopter type constructed with two sustaining surfaces provided according to one of the patents before referred to; in this figure 2, 2 are the surfaces to which a movement of rotation is given by one or two motors provided in the car 14. In this car are also provided the fans driven by the motor or motors, these fans drawing in air and passing it to the upper side of the surface in the manner which has been described.

It will be understood that instead of employing air any other gas which may or may not be mixed with liquid may be used. The fan may be dispensed with and a gas under pressure contained in a suitable receptacle may be employed in its place.

The invention may be applied to rotary surfaces for traction and propulsion as well as to sustaining surfaces; it is more especially suitable for application to the rotary surfaces described in the patents before referred to, but it is needless to say that it might also be applied to rotary surfaces of any other form provided on the principle hereinbefore mentioned, that is to say, on the reduction of pressure effected at the front or upper face of a surface having a

rotary movement around an axis normal to the surface. The same device may of course, be applied to navigation in or on water by directing a fluid or a liquid under the same conditions over the surfaces in motion. Finally, surfaces thus provided may be employed as aerial tractors on water and on land.

What I claim as my invention and desire to secure by Letters Patent is:—

1. The combination of a rotatable surface or plane of a form such that on its rotation a reduction of pressure of the medium in which the surface or plane rotates results at one of the faces of the surface or plane, with means for directing gas or fluid under pressure radially outward for the purpose of increasing the said reduction of pressure.

2. The combination of a rotatable surface or plane of a form such that on its rotation a reduction of pressure of the medium in which the surface or plane rotates results at one of the faces of the surface or plane, with means for directing gas or fluid under pressure radially outward for the purpose of increasing the said reduction of pressure and means for supplying gas or fluid under pressure to the other face of the surface or plane for the purpose of reducing or destroying the partial vacuum created at the center by the rotation of the surface or plane.

3. The combination of a rotatable surface or plane of a form such that on its rotation a reduction of pressure of the medium in which the surface or plane rotates results at one of the faces of the surface or plane, with a disk or plate coaxially disposed adjacent the said face and means for directing gas or fluid under pressure to the center of the space between the disk or plate and the surface or plane and radially outward over the face thereof.

4. The combination of a rotatable surface or plane of a form such that on its rotation a reduction of pressure of the medium in which the surface or plane rotates results at one of the faces of the surface or plane, with a hollow shaft on which the surface or plane is mounted, means for supplying gas or fluid to the hollow shaft, and a deflector plate coaxially disposed adjacent the said face of the surface or plane and adapted to deflect the gas or fluid radially outward over the surface or plane.

5. The combination of a rotatable surface or plane of a form such that on its rotation a reduction of pressure of the medium in which the surface or plane rotates results at one of the faces of the surface or plane, with a hollow shaft on which the said surface or plane is mounted, a fan forcing gas or fluid under pressure into the hollow shaft, means for driving the fan, and a deflector plate co-axial with the hol-

low shaft and adjacent the outer end thereof and the said face of the surface or plane, the said deflector plate being adapted to deflect the gas or fluid radially outward 5 over the said face of the surface or plane to increase the speed of the said medium passing toward the periphery of the surface or plane.

6. The combination of a rotatable surface 10 or plane of a form such that on its rotation a reduction of pressure of the medium in which the surface or plane rotates results at one of the faces of the surface or plane, with a plate or disk co-axially disposed adjacent the said face of the surface or plane, a conduit for gas or fluid under pressure terminating in an orifice in the center of the said surface or plane, and means for supplying gas or fluid under 15 pressure to the said conduit.

7. The combination of a rotatable surface or plane of a form such that on its rotation a reduction of pressure of the medium in which the surface or plane rotates results at one of the faces of the surface or plane, with a plate or disk co-axially disposed adjacent the said face of the surface or plane, a conduit for gas or fluid under pressure terminating in an orifice in the 20 center of the said surface or plane, a fan for supplying gas or fluid under pressure to the said conduit and means for driving the said fan.

8. The combination of a rotatable surface 25 or plane of a form such that on its rotation a reduction of pressure of the medium in

which the surface or plane rotates results at one of the faces of the surface or plane, with a plate or disk co-axially disposed adjacent the said face, means for supplying 30 gas or fluid under pressure to the center of the space between the said plate or disk and the surface or plane so that the gas or fluid is deflected radially outward, and means for supplying gas or fluid under 35 pressure to the other face of the surface of plane.

9. The combination of a rotatable surface or plane of a form such that on its rotation a reduction of pressure of the medium in 40 which the surface or plane rotates results at one of the faces of the surface or plane, a hollow shaft upon which the said surface or plane is mounted, a deflector plate adjacent the end of the hollow shaft and the 45 said face of the surface or plane, means for forcing gas or fluid under pressure through the hollow shaft to impinge upon the said plate or disk so as to be deflected radially outward, a hollow sleeve surrounding the said shaft with an open end adjacent the other face of the surface or plane, and means for forcing gas or fluid under 50 pressure through the said sleeve to the surface or plane.

In testimony whereof I have hereunto signed my name to this specification in the presence of two subscribing witnesses.
